DISHWASHING MACHINE

Kurt Albrecht, Pittsburgh, Pa., assignor to John
M. Hopwood, Mount Lebanon, Pa.

Application April 18, 1938, Serial No. 202,628

3 Claims. (Cl. 141—9)

This invention relates to mechanical dishwashing machines of the type utilizing a detergent wash solution, which is pumped from a solution tank through spray nozzles onto the dishes to remove soil, and employing rinse nozzles for spraying the dishes with plain rinse water after the soil has been removed by the washing action of the detergent solution.

In prior art machines of the type referred to above the construction and design was such that the rinse water discharged into the wash solution thereby diluting the same and impairing, in some cases actually destroying, its effectiveness. In some cases the solution in the tank would be changed as high as seventeen times per hour; obviously, unless an excess amount of detergent material was added to the tank, the wash solution would be diluted to only a fraction of its original strength. Therefore, to maintain the detergent solution at its proper strength or concentration, so much material had to be added to the solution that the cost of detergent material was excessive; while if detergent was not added, the concentration of the wash solution was reduced so much that it was ineffective or so slightly effective that soil could not be thoroughly removed from the dishes.

An object of this invention is to provide mechanical dishwashing machines with means whereby the concentration of the detergent solution may be maintained at any desired value through such control of the rinse water that none of it, or only a small portion of it, is allowed to enter the detergent solution to dilute it.

Another object of the invention is to provide means that may be made to function automatically to prevent dilution of the detergent washing solution when the supply of wash solution to the wash arms or nozzles is cut off.

Other objects of the invention will, in part, be obvious, and will, in part, be apparent from the following description taken in conjunction with the accompanying drawing in which a mechanical dishwashing machine embodying one form of the invention is more or less diagrammatically illustrated.

The machine illustrated in the drawing comprises a wash chamber 1 provided with a perforated bottom or support 2 on which is a rack 3 containing dishes 4 to be washed.

The rack is placed in the machine through doors or openings 5 in position to be washed with a detergent solution which is sprayed over the dishes by means of a spray head or wash

arm 6 having spray nozzles or jets 7 associated therewith.

The wash solution is stored in a tank or receptacle 8 into which the solution is directed as it runs off the dishes through support 2. The wash solution is pumped from tank 8 by means of a motor-driven pump 9 and delivered through a pipe 10 to the spray head 6 at such pressure that the solution leaves nozzles 7 with sufficient velocity to effect thorough and rapid removal of soil from the dishes.

When the dishes have been subjected to the washing action of the detergent solution for a sufficient length of time to insure removal of all soil, the dishes are rinsed with plain water. Before rinsing, however, the pump is stopped to shut off the supply of wash solution to the spray head. Rinsing may be effected by means of nozzles 7 or by a separate spray head and nozzle assembly. For the sake of illustration, it can be assumed that nozzles 7 are also used for rinsing purposes. To utilize nozzles 7 for rinsing purposes, two valves 11 and 12 may be employed, valve 11 being closed (after pump 9 has been stopped), to prevent delivery of rinse water through pipe 10 to tank 8, and valve 12 being opened to connect spray head 6 to a rinse water supply pipe 13.

In order to prevent dilution of the detergent solution by the rinse water, means 14 are provided for intercepting the rinse water and directing it to a drain.

Means 14 comprises a plate or cover 15 extending over the top of tank 8 having an opening 16 therein to which a tube 17 is connected, and an overflow tube or pipe 18 disposed within tube 17 and having its top located at a point well above the normal level 19 of the detergent wash solution of tank 8. The lower end of tube 18 is connected to a drain pipe 20.

Tube 17 extends downwardly from plate 15 to a point near the bottom of tank 8 and is substantially larger in diameter or cross-sectional area than tube 18. Liquid, whether it be detergent wash solution or rinse water, falls on plate 15, which for practical reasons is so formed as to slope from all sides towards opening 16.

When valve 11 is open (valve 12 being then closed) and pump 9 is operating to deliver wash solution to spray nozzles 7, the level of the wash solution drops in tank 8 to a level such as indicated by line 21 so that as the wash solution falls from or is delivered from chamber 1 onto plate 15, the liquid in running into the space between tubes 17 and 18 will not overflow into

tube 18. As soon as pump 9 is stopped the level will rise in tank 8 to say level 19. When rinse water is turned on to nozzles 7, by closing valve 11 and opening valve 12, the water discharging from chamber 1 runs into opening 16 filling the space above the liquid level 19 and between tubes 17 and 18 so that the rinse water may overflow into 18 and thence to drain via pipe 20. Because of the relatively long confined space between tubes 17 and 18 which extends from approximately the top to the bottom of tank 8, rinse water will not flow into the body of wash solution of tank 8 and dilute it. The only dilution that can occur results from the relatively small amount of water 15 that settles into the detergent solution confined between tubes 17 and 18 and that which is held on the surface of the column of fluid between them at levels below the top of tube 18.

Plate 15 and tubes 17 and 18 arranged as described above form in effect an automatic trap or overflow that operates to allow free circulation of detergent solution from tank to wash nozzles to tank without losing any solution through the drain, and effect automatic discharge of rinse 25 water to drain without diluting the detergent solution. What little dilution that does occur is beneficial and not detrimental or wasteful of detergent.

When a machine is provided with means for intercepting rinse water and passing it off to drain as above described, the concentration of the detergent wash solution can be maintained at its effective value with small additions of detergent, thereby insuring economy in the use of 30 detergents. Where no provision is made for preventing excess dilution, the wash solution in many cases undergoes as many as seventeen changes per hour requiring from ten to fifteen times as much detergent chemical as would be needed to 35 provide a solution of the desired and effective concentration where dilution is controlled as herein described.

Having thus described the invention, what I claim as new and desire to secure by Letters Patent is:

1. In a dishwashing machine provided with a wash chamber, a receptacle for detergent solution adapted to receive wash solution from the wash chamber, means for spraying dishes with wash solution from said receptacle, and means for delivering water to the spraying means for rinsing dishes in the wash chamber, the improvement which is characterized by the fact that the wash solution receptacle is provided with a relatively restricted passage extending from the top

to a point near the bottom thereof, through which wash solution is returned from the wash chamber to the body of solution in the receptacle, and a second passage disposed within the first-mentioned passage and which is open at a point above the normal level of the wash solution in said receptacle and adapted to carry liquid overflowing into the same to a drain, whereby when said solution spraying means is operating, said solution may flow from the wash chamber through 10 said first-mentioned passage to the solution tank and thence to the spray means, and when said solution spraying is stopped and rinse water is delivered to the wash chamber, the rinse water collects at the top of said first-mentioned passage and overflows through the other passage to drain.

2. A wash solution supply receptacle for mechanical dishwashing machines of the jet-type 20 adapted to be connected to a pump supplying the jets and receiving wash solution returned from said jets, said receptacle having a closed top provided with an opening therein, a tube connected to said opening and extending downwardly 25 into said receptacle for conveying return wash solution to the interior of said receptacle, and an overflow tube disposed within said first-mentioned tube in spaced relation thereto and having its upper end disposed above the normal level 30 of wash solution contained in said receptacle and having its lower end connected to a drain outlet, said overflow tube being operative to allow rinse water to collect in the space between said tubes 35 on top of the wash solution and overflow into it to drain without substantially diluting said wash solution.

3. A wash solution supply receptacle for mechanical dishwashing machines of the jet type 40 adapted to be connected to a pump supplying the jets and receiving wash solution returned from said jets, said receptacle having a closed top provided with an opening therein and a tube connected to said opening and extending downwardly 45 into said receptacle for conveying return wash solution to the interior of said receptacle, there being an overflow outlet associated with said tube the outlet opening of which is located above the normal level of wash solution contained in said receptacle, said overflow outlet being operative 50 to allow rinse water collecting in said tube on top of the wash solution therein to overflow to drain without substantially diluting said wash solution.
